VEHICLE FRAME AND BACKHOE ATTACHMENTS

Gerard S. Gremillion, 50 E. 54th St., Kansas City, Mo.
64112, and Bert M. McMillin, 10120 Wenonga Lane,
Leawood, Kans.

Filed Mar. 22, 1971, Ser. No. 127,070

Term of patent 14 years

Int. Cl. D12—13

U.S. Cl. D14—3 R

FIG. 1 is a top plan view of a vehicle frame and backhoe embodying the attachments' unique design;

FIG. 2 is a side elevational view of the vehicle frame and backhoe attachments shown in FIG. 1;

FIG. 3 is a side elevational view of the side opposite that shown in FIG. 2; and

FIG. 4 is a rear and elevational view of the vehicle frame and backhoe attachments shown in FIG. 3.

The vehicle shown in broken lines in FIG. 2 is included for illustrative purposes only.

We claim:

The ornamental design for a vehicle frame and backhoe attachments, as shown and described.
